UNITED STATES PATENT OFFICE.

FREDERICK C. SELK, OF IRONWOOD, MICHIGAN.

DESIGN FOR AN ICE-SHAVE.

SPECIFICATION forming part of Design No. 34,656, dated June 11, 1901.

Application filed May 7, 1901. Serial No. 59,185. Term of patent 7 years.

To all whom it may concern:

Be it known that I, FREDERICK C. SELK, a citizen of the United States, residing at Ironwood, in the county of Gogebic and State of Michigan, have invented and produced a new and useful Design for Ice-Shaves, of which the following is a specification.

My invention relates to new and useful designs in ice-shaves, of which the following is a specification, reference being had to the accompanying drawings, forming a part thereof.

Figure 1 is a front elevation showing my new design. Fig. 2 is a rear elevation.

Like numerals of reference designate like parts in both views of the drawings.

My design comprises a rectangular portion 1, having on its lower edge a series of teeth 2, beveled on both sides at 3. Spurs 4 jut out from the sides 5 of the portion 1, and a

tapering portion 6 extends upward from the 20 spurs 4 and ends in a point at 7.

The essential or material features of my design are the rectangular portion 1, having beveled teeth 2 and spurs 4 thereon, and the tapering portion 6. 25

Having described my invention, what I claim as new, and wish to secure by Letters Patent, is—

The design for an ice-shave, substantially as shown and described. 30

In testimony whereof I have hereunto set my hand in presence of two subscribing witnesses.

FREDERICK C. SELK.

Witnesses:

CURTIS BUCK,
F. A. MILLER.
